UNITED STATES PATENT OFFICE.

EDSEL MILLER, OF MOUNT STERLING, ILLINOIS.

FIRE-ESCAPE.

No. 923,555.

Specification of Letters Patent.

Patented June 1, 1909.

Application filed August 25, 1908. Serial No. 450,138.

To all whom it may concern:

Be it known that I, EDSHEL MILLER, a citizen of the United States, and a resident of Mount Sterling, in the county of Brown 5 and State of Illinois, have invented a new and Improved Fire-Escape, of which the following is a full, clear, and exact description.

My invention relates to fire escapes, and 10 in substance it consists of a frame in which a drum is mounted to rotate, there being a gear wheel secured to the drum, which meshes with a gear wheel secured to a shaft journaled in the frame, there being governor 15 members secured to the said shaft, the governor members having inner undulating parallel surfaces, the inner undulating parallel surfaces engaging a shank having an eye which is freely mounted on the shaft be- 20 tween the governor members, the diameter of the shank being nearly as great as the space between the undulating surfaces of the governor members. A cable is wound on the drum, and a spring is secured to the drum 25 to press the cable into place when being wound on the drum. A crank is also provided to rotate the drum to wind the cable.

Still other objects of the invention will 30 appear in the following complete description.

In this specification I will describe the preferred form of my invention, but it will be understood that I do not limit myself thereto as I consider myself entitled to all 35 forms and embodiments of the invention which may be held to fall within the scope of the appended claims.

Reference is to be had to the accompanying 40 drawings, forming a part of this specification, in which similar characters of reference indicate corresponding parts in all the figures, in which—

Figure 1 is a front elevation of the invention; Fig. 2 is a sectional view on the line 45 2—2 of Fig. 1; and Fig. 3 is a sectional view showing a portion of the shaft on which the governor members are mounted and the shank disposed between the governor members.

50 By referring to the drawings, it will be seen that side frame members 1 are provided, and that these frame members are united at the top and bottom by frame members 2, the upper frame member 2 being disposed at 55 the rear of the side members 1, so that it will not interfere with a shank 3. In the

side frame members 1 is journaled a shaft 4 to which is secured a drum 5 and a gear wheel 6. The shaft 4 extends some distance through one of the side frame members 1, so 60 that a crank 7 may be applied to rotate the drum. A cable 8 is wound on the drum 5 and a spring 9 is secured to the frame, the spring pressing on the cable 8 wound on the drum to hold it in place when being wound. 65 Above the shaft 4 a second shaft 10 is journaled in the side frame members 1, and a gear wheel 11 is mounted on this shaft 10, the gear wheel 11 being adapted to slide laterally, but when the gear wheel 11 is dis- 70 posed over the gear wheel 6 the two gear wheels mesh, and when the gear wheel 11 is in this position a screw 12, which passes through an offset 13, secured to the gear wheel, is adapted to be screwed into the 75 shaft 10 to hold the gear wheel 11 in position. Secured to the shaft 10 are governor members 14, the governor members 14 having inwardly disposed annular flanges 15, the extremities of the said flanges 15 having 80 undulating surfaces which are parallel with each other. The shank 3 has a ring 16 which is freely mounted on the shaft 10 between the governor members 14, but inasmuch as the diameter of the said shank 3 is only 85 slightly less than the distance between the undulating surfaces of the flanges 15, it will be seen that when the shank 3 is held ex- 90 tended relatively to the frame and the shaft 10 is rotated, that the undulating surfaces of the flanges 15 will cause the shank to move to and fro laterally, and as there is considerable friction between the said shank 3 and the undulating surfaces of the flanges 15, the rotation of the shaft 10 will be con- 95 siderably limited.

In using my invention, the shank 3 may be supported by means of links 17, or otherwise, to a fixture 18, and when the cable 8 is wound on the drum 5, by means of the crank 100 7, the fire escape is in position to be operated. The cable 8 may be fastened directly to the body of a person or it may be fastened to a belt which is fastened around the body of the person who is to be rescued. The crank 105 7 is of course, removed from the shank 4, and the body which is being rescued is then disposed so that the weight will bear on the cable and will rotate the drum 5, and by means of the gear wheels 6 and 11 will rotate 110 the shaft 10, but inasmuch as the rotation of the shaft 10 will be retarded by means of the

friction of the shank 3, on the undulating surfaces of the flanges 15, the rotation of the drum 5 will also be retarded and it will be possible for the body to reach the ground, 5 moving at a safe speed. It will, of course, be understood that if desired, a cage may be secured to the cable 8 to permit the lowering of a number of persons at one time.

Having thus described my invention, I 10 claim as new and desire to secure by Letters Patent:

1. In a fire escape, a frame, a shaft journaled therein, two governor members spaced apart and secured to the shaft, the governor 15 members having inner undulating surfaces disposed parallel with each other, and a shank mounted freely on the shaft between the governor members.

2. In a fire escape which is adapted to afford communication with the ground from a 20 distance thereabove, a frame, a shaft journaled therein, means for rotating the shaft, a shank freely mounted on the shaft, the shank forming a unit in the said communication 25 with the ground, and means adapted to move the shank to and fro longitudinally of the shaft as the shaft rotates.

3. In a fire escape, a frame, a shaft journaled therein, two governor members spaced 30 apart and secured to the shaft, each of the governor members having an annular inwardly disposed flange, the extremities of the flanges having undulating surfaces which are parallel with each other, and a shank 35 mounted freely on the shaft between the governor members.

4. In a fire escape, a frame, a drum mounted to rotate therein, a gear wheel secured to the drum, a shaft journaled in the frame, a 40 gear wheel secured thereto, the last named gear wheel meshing with the gear wheel on the drum, two governor members spaced

apart and secured to the shaft, the governor members having inner undulating faces disposed parallel with each other, and a shank 45 mounted freely on the shaft between the governor members.

5. In a fire escape, a frame, a drum mounted to rotate therein, a cable wound on the drum, a shaft journaled in the frame, means 50 by which the drum is adapted to drive the shaft, a shank freely mounted on the shaft, and means in connection with the shank to retard the rotation of the shaft.

6. In a fire escape, a frame, a drum mounted to rotate therein, a cable wound on the drum, a shaft journaled in the frame, means 55 by which the drum is adapted to drive the shaft, means to press the cable in place on the drum, a shank mounted freely on the 60 shaft, and means to move the shank to and fro laterally as the shaft rotates.

7. In a fire escape which is adapted to afford communication with the ground from a 65 distance thereabove, a frame, a shank freely mounted in the frame which forms a unit in the said communication with the ground, a shaft, and means in connection with the shank which are adapted for retarding the 70 rotation of the shaft.

8. In a fire escape which is adapted to afford communication with the ground from a 75 distance thereabove, a frame, a shank freely mounted therein which forms a unit in the communication to the ground, a shaft, and means for moving the shank to and fro as the shaft rotates.

In testimony whereof I have signed my name to this specification in the presence of two subscribing witnesses.

EDSEL MILLER.
